H. J. SOMMER AND J. REIGH,
MOP HOLDER,
APPLICATION FILED APR. 26, 1920.

1,358,399.

Patented Nov. 9, 1920.

BY

Lacey & Lacey,
ATTORNEYS

UNITED STATES PATENT OFFICE.

HENRY J. SOMMER AND JACOB REIGH, OF HOLLIDAYSBURG, PENNSYLVANIA.

MOP-HOLDER.

1,358,399.

Specification of Letters Patent.

Patented Nov. 9, 1920.

Application filed April 26, 1920. Serial No. 376,715.

To all whom it may concern:

Be it known that we, HENRY J. SOMMER and JACOB REIGH, citizens of the United States, residing at Hollidaysburg, in the 5 county of Blair and State of Pennsylvania, have invented certain new and useful Improvements in Mop-Holders, of which the following is a specification.

This invention relates to improvements in 10 mop heads and has as its primary object to provide a head of simple and inexpensive construction in which may be readily clamped a mop or mop cloth of any ordinary thickness.

15 Another object of the invention is to so construct the head that the retaining member for the mop may be quickly released and swung clear of the mop for the purpose of removing the mop from the head and may 20 equally as readily be swung into engagement with a mop to be secured in place upon the head, both operations being performed without the necessity of resorting to the use of tools of any sort.

25 In the accompanying drawings:

Figure 1 is a perspective view of the device embodying the present invention;

Fig. 2 is a vertical longitudinal sectional view through the mop head;

30 Fig. 3 is a vertical transverse sectional view taken substantially on the line 3—3 of Fig. 2.

In the drawings the numeral 1 indicates the mop stick or handle which is provided 35 at its lower end with the usual ferrule 2 and which has permanently secured thereto a yoke 3 the arms of which are secured at their lower ends to the fixed member of the mop head. This member is indicated in general 40 by the numeral 4 and the same preferably comprises an elongated plate which is transversely curved throughout its length substantially to semi-circular form as clearly shown in Figs. 1 and 3 of the drawings, 45 the concave side of the head being presented downwardly. At one end the member 4 is formed with an opening 5 in which is pivotally engaged a closed eye 6 formed at one end of the clamping member of the head 50 which member is indicated by the numeral 7. This member is preferably in the form of a stout wire or small rod provided as stated at one end with the eye 6 and it is preferable that adjacent the point of juncture of the 55 eye with the body of the member 7 the said

member be given an upward curve as indicated by the numeral 8 so that when the member is in the locking or clamping position shown in Fig. 2 of the drawings there will be sufficient space between this end of 60 the body of the member and the corresponding end of the member 4 to accommodate the mop or mop cloth which is indicated by the numeral 9.

A stem 10 is pivoted as at 11 at the other 65 or free end of the clamping member 7 and this stem is threaded throughout the greater portion of its length as indicated by the numeral 12 and is designed to be swung upon its pivot in the clamping position of 70 the member 7, so as to project upwardly through a notch 13 which is formed in that end of the member 4 opposite the end in which the opening 5 is formed. A clamping nut 14 is threaded onto the stem 12 and 75 is provided with a wing 15 which may be grasped for the purpose of rotating it upon the stem, the nut 14 being designed to bear against the upper side of the notched end of the member 4 in the manner clearly shown 80 in Figs. 1 and 2 of the drawings.

From the foregoing description of the invention it will be understood that the mop 9 is clamped in the head 6 engaging the intermediate portion of the said mop in the 85 channelled under side of the member 4 and then swinging the clamping member 7 to clamping position as shown particularly in Figs. 2 and 3 of the drawings, the stem 10 being swung to position projecting through 90 the notch 13, and the clamping nut 14 being turned down upon the stem until the mop has been sufficiently firmly clamped by the member 7 and between this member and the said member 4. When it is desired to remove the mop it is only necessary to loosen the nut 14 and disengage the stem 10 from the notch 13 whereupon the clamping member 7 may be swung downwardly for the purpose stated.

Having thus described the invention, what is claimed as new is:

1. A mop head comprising a fixed clamping member, a movable clamping member pivoted at one end to one end of the first 105 mentioned member, the first mentioned member being formed at its other end with a notch, a stem pivotally connected with the free end of the movable clamping member and engageable in the notch, and a binding 110

nut threaded onto the said stem and engaging the upper side of the notched end of the first mentioned member.

2. A mop head comprising a relatively fixed clamping member provided at one end with an opening and at its other end with a notch, a movable clamping member comprising a rod upturned near one end and beyond its upturned portion formed with an eye 10 pivotally engaged through the opening in

the first mentioned member, a stem pivotally connected with the free end of the movable clamping member and engageable in the said notch, and a binding nut threaded onto the said stem.

15 In testimony whereof we affix our signatures.

HENRY J. SOMMER. [L.S.]
JACOB REIGH.
